United States Patent Office

Des. 228,836
Patented Oct. 30, 1973

228,836

SOFÁ

Thomas Winrow, Naperville, Ill., assignor to Mohasco
Industries, Inc., Amsterdam, N.Y.

Filed Apr. 22, 1971, Ser. No. 136,650

Term of patent 14 years

Int. Cl. D6—02

U.S. Cl. D6—63

FIG. 1.

FIG. 2.

FIG. 1 is a perspective view of a sofa illustrating my new design. FIG. 2 is another perspective view of a sofa illustrating the design of the instant invention. The back of the sofa is conventionally plain.

I claim:

The ornamental design for a sofa, as shown and described.
